CLAIM

The ornamental design for a serving dish, as shown and described.

DESCRIPTION

FIG. 1 is a top, right side and front perspective view of a first embodiment of a serving dish showing the new design; FIG. 2 is a front elevation view thereof, the rear elevation being identical thereto;

FIG. 3 is right side elevation view thereof, the left side being identical thereto;

FIG. 4 is a top plan view thereof;

FIG. 5 is a bottom view thereof;

FIG. 6 is a top, right side and front perspective view of a second embodiment of a serving dish showing the new design;

FIG. 7 is a front elevation view thereof, the rear elevation being identical thereto;

FIG. 8 is a right side elevation view thereof, the left side being identical thereto;

FIG. 9 is a top plan view thereof; and,

FIG. 10 is a bottom plan view thereof.
